UNITED STATES PATENT OFFICE.

JOHN LUTZ AND CHARLES J. LEYES, OF JERSEY CITY, NEW JERSEY.

MACHINE FOR EXHIBITING RUGS.

1,065,378.

Specification of Letters Patent.

Patented June 24, 1913.

Application filed January 22, 1913. Serial No. 743,506.

To all whom it may concern:

Be it known that we, JOHN LUTZ and CHARLES J. LEYES, citizens of the United States, and residing at Jersey City, in the county of Hudson and State of New Jersey, have invented certain new and useful Improvements in Machines for Exhibiting Rugs, of which the following is a specification, such as will enable those skilled in the art to which it appertains to make and use the same.

This invention relates to machines or apparatus for exhibiting or displaying rugs to purchasers, and the object thereof is to provide an improved apparatus of this class which is designed for use by dealers in rugs, carpets and like articles, for the purpose of easily and conveniently displaying their merchandise, and particularly for the purpose of displaying rugs in a spread out or horizontal position.

The invention described and claimed herein is an improvement on that described and claimed in an application for Letters Patent of the United States, filed by us August 8, 1912, Ser. No. 713,993, and is fully disclosed in the following specification of which the accompanying drawings form a part, in which the separate parts of our invention are designated by suitable reference characters in each of the views, and in which;—

Figure 1 is a side view of our improved rug displaying machine, the right hand portion thereof being shown in section;—Fig. 2 a plan view of the left end portion of the machine as shown in Fig. 1;—Fig. 3 a view looking at the right end portion of the machine, and on an enlarged scale and with part of the construction broken away;—Fig. 4 a section on the line 4—4 of Fig. 3, and Fig. 5 a side view of a machine similar to that shown in Figs. 1, 2 and 3, but showing a modification.

In the practice of our invention, as shown in the drawings, we provide a suitable oblong base *a* the end portions of which are provided with transversely arranged uprights *b* and *c*, inwardly of which and at predetermined distances from the uprights *b* and *c* are other transversely arranged uprights *d* and *e*.

Mounted on the transversely arranged uprights *d* and *e* is a stationary table *f* at the opposite ends of which are placed transverse rollers *f²* and *f³*, and secured to the top portion of the transversely arranged uprights

d and *e* are outwardly and upwardly curved bracket arms *f⁴* and *f⁵* to which are hinged supplemental end table members *f⁶* and *f⁷* to the bottoms of which are secured, as shown at *f⁸* and *f⁹*, inwardly directed curved arms *g* and *g²* which are provided at their inner ends with weights *g³* and *g⁴*.

In the top portion of the uprights *b* and *c* are mounted rollers *h* having shafts *h²*, and on the front end portions of which are loosely mounted large gears *h³* having central ratchets *h⁴*, and in said uprights, below the rollers *h* are mounted stub shafts *h⁵* provided with smaller gears *h⁶* and pinion shafts *h⁷* which mesh with the gears *h³*. Mounted in said uprights below the stub shafts *h⁵* are other stub shafts *h⁸* provided with pinions *h⁹* which mesh with gears *h⁶*, and the shafts *h⁸* are also provided with gears *h¹⁰* and placed adjacent to the end portions of the machine are electric motors *i* having shafts *i²* provided with small gears or pinions *i³* which mesh with the gears *h¹⁰*.

Slidably mounted on the shafts *h²* adjacent to the ratchets *h⁴* of the gears *h³* are clutch disks *j* provided, in the form of construction shown, and at the top and bottom edges with inwardly directed fingers *j²* which are adapted to engage the ratchets *h⁴*, and said clutch disks are also preferably provided at the top thereof with finger piece *j³*.

We also provide a flexible strip or sheet *k* composed of fabric or any other suitable material which may be of any preferred length, and which is placed longitudinally of the table *f*, and the ends thereof are connected with the rollers *h*, and on the strip *k* are placed the rugs *m* to be displayed, and in practice said strips with the rugs thereon may be wound onto one of said rollers and then rewound onto the other roller, and this operation may be repeated as often as desired and the rugs *m* may thus be exposed in a spread out form for inspection.

Suppose the parts to be in the position shown in the drawing with the strip or sheet *k* wound on the left roller *h* and it be desired to rewind it onto the right roller. The clutch *j* of the right roller *h* is thrown into operative position, as shown in Fig. 3, and the clutch of the left roller *h* is drawn out of operation, and the right motor *i* is started, this will result in the winding of the rugs and the strip or sheet *k* onto the right roller *h*, and when it is desired to rewind said strip and rugs on the left roller

h, this operation is reversed, the clutch *j* on the left roller *h* is thrown into operation while the corresponding clutch on the right roller *h* is thrown out of operation, as shown in dotted lines in Fig. 3, and the left motor *i* is started.

In the above described operation, the hinged table members *f⁶* and *f⁷* bear on the bottoms of the rollers *h* at all times, and 10 in this way the roller from which the strip or sheet *k* is being unwound will be prevented from racing or turning too freely.

This invention is not limited to the use 15 of the motors *i* as herein described, nor to any particular form of gearing for transmitting the movement of the shafts *i²* of said motors to the rollers *h*, and any suitable means may be provided for turning said rollers alternately, and if desired said 20 rollers may be turned by hand. In Fig. 5 of the drawing, however, we have shown a construction whereby the speed of the roller onto which the strip or sheet *k* is being wound may be automatically reduced as said 25 strip or sheet is wound thereon so that the speed or movement of the said strip or sheet will not be increased as the dimensions of the said roller increase. In order to accomplish this result, we place at each end 30 of the machine, a rheostat *n* and connect with the bottom of the hinged end members *f⁶* and *f⁷*, and preferably centrally thereof, link devices *o* which are also connected with the arms *n²* of the rheostats *n*. The rheostats *n* are provided with circuit wires *n³* and *n⁴* which are connected with the circuit wires of the motors *i* and said rheostats, in 35 the form of construction shown, are provided with a plurality of contact points *n⁵*, and as the table members *f⁶* and *f⁷* move downwardly the rheostats will be operated 40 to decrease the speed of the motors, as will be readily understood. In this form of construction we substitute for the weighted 45 arms *g* and *g²* springs *p* and *p²* which are secured to the transversely arranged uprights *d* and *e* and which bear on the bottoms of the table members *f⁶* and *f⁷* and

cause said table members to bear on the bottoms of the rollers *h* at all times. The rollers *f²* and *f³* are also omitted, but otherwise the construction and operation of the machine is the same, as that shown in Figs. 1 to 4 inclusive.

Other means may be provided for regulating the movement of the rollers *h*, and a single motor may be employed for operating said rollers and for regulating the movement thereof, if desired, and other changes in and modifications of the construction described may be made, within the scope of the appended claim, without departing from the spirit of our invention or sacrificing its advantages.

Having fully described our invention 65 what we claim as new and desire to secure by Letters Patent is;—

A rug displaying machine comprising a base, rollers supported above the end portions of said base, a horizontal table supported between said rollers and provided with movable end members adapted to bear on the bottom thereof, a display strip or sheet of predetermined length passed longitudinally over said table and the end members thereof, and the ends of which are connected with said rollers, motors geared in connection with said rollers, clutch devices whereby said rollers may be alternately thrown into or out of operation so as to wind said strip or sheet first on one and then on the other, and devices operated by the movable end members of the table and in connection with the motors for reducing the speed of each of said rollers as said strip or sheet is wound thereon.

In testimony that we claim the foregoing as our invention we have signed our names in presence of the subscribing witnesses this 17th day of January, 1913.

JOHN LUTZ.
CHARLES J. LEYES.
